Primary Examiner — Selina Sikder

(74) *Attorney, Agent, or Firm* — Robert C. Montgomery; Montgomery Patent & Design, L.P.

(57) **CLAIM**

The ornamental design for a remote-controlled door opener module, as shown and described.

DESCRIPTION

FIG. 1 is a perspective top view of a remote-controlled door opener module, showing my new design;

FIG. 2 is a front side elevation view thereof;

FIG. 3 is a rear side elevation view thereof;

FIG. 4 is left side elevation view with the right side elevation view being a mirror image thereof;

FIG. 5 is a top side plan view thereof; and,

FIG. 6 is a bottom side plan view thereof.

The broken lines indicate boundary areas and form no part of the claimed design.

1 Claim, 6 Drawing Sheets
